PORTABLE CARRYING CASE

Leo Stein, Chicago, Ill.

Application May 27, 1940, Serial No. 337,374

14 Claims.

(Cl. 281—17)

This invention relates to portable carrying cases, and particularly to a case designed primarily for carrying large quantities of catalogues, sheets, blue prints, etc., in loose-leaf devices or binders.

Heretofore, when salesmen, for example, have been required to carry large quantities of loose-leaf materials, such as catalogues, specifications, price lists, etc., it has been necessary to use wide, bulky, inconvenient catalogue cases, wherein the catalogues are placed flat on the bottom. Such cases are usually made of flexible material, thick laterally and susceptible to bulging due to the contents of the case, thus causing the case to strike against one's legs when carrying, thereby producing undue wear on one's clothing. Furthermore, due to the flexibility of the material from which such cases are constructed, the contents of the case would soon cause the bottom to sag and the case to become out of shape, very unsightly, uncomfortable to carry and awkward to handle.

One object, therefore, of the present invention is to provide a carrying case for catalogues and the like, which is of substantial construction, of maximum capacity and of minimum thickness.

Another object of the invention is to provide a carrying case wherein loose-leaf devices may be installed in the sides of the case thereby contributing materially to the elimination of bulk and a reduction in thickness of a case capable of holding the desired quantity of material.

Another object of the invention is to provide a carrying case of the character described, so constructed that when open to provide accessibility to the contents thereof, the case will assume a substantially L-shaped position, and occupy a minimum amount of space on a table, desk or the like.

Another object of the invention is to provide a strong, durable case of substantial construction, which will not bulge or sag out of shape from the weight of the contents.

Another object of the invention is to provide a carrying case of novel construction and arrangement wherein the contents thereof are securely held in fixed position and suitably supported when the case is in closed or carrying position.

A further object of the invention is to provide a case of the character described, which is of simple construction, readily accessible, convenient and comfortable to handle, efficient in its operation and suitable for the purpose intended.

A still further object of the invention is to

improve devices of the character described in sundry details hereinafter referred to and particularly pointed out in the appended claims.

One embodiment of the present invention is shown for illustrative purposes in the accompanying drawings in which:

Fig. 1 is a perspective view of a portable carrying case shown in open position and embodying features of the present invention;

Fig. 2 is a vertical transverse sectional elevational view of my improved carrying case shown in closed position, and taken substantially as indicated by the lines 2—2 of Fig. 3;

Fig. 3 is a plan sectional view of the structure illustrated in Figs. 1 and 2, and taken substantially as indicated by the line 3—3 of Fig. 2;

Fig. 4 is a fragmentary sectional elevational view of a portion of the structure illustrated in Fig. 1, and taken substantially as indicated by the line 4—4 thereof; and

Fig. 5 is a perspective view of a quantity of sheet material mounted in a loose-leaf binder which may be of any type employed in connection with the present invention.

As illustrated in the drawings, the present invention comprises a comparatively narrow or shallow elongated body member indicated as a whole by the numeral 11, and having a base portion 12 to which a cover member indicated as a whole by the numeral 14 is hinged or connected at 13 along one of the long edges.

For supporting a quantity of sheet material indicated at 15, bound together in binders of any preferred style, for illustration shown in the present instance, as a pair of binding strips 16 in the carrying case 11, the cover member 14, preferably, is provided with a binder retainer indicated as a whole by the numeral 17 secured to the inner side of the cover and extending transversely therein.

The retainer, shown in the present instance, is positioned on the cover member at one side of a plane extending transversely to the cover member adjacent the central portion thereof, preferably adjacent the end of the cover member 14 or, broadly speaking, between one end of the cover and an intermediate position. The style and design of the retainer will depend upon the particular type of binder used and in some instances the binder and retainer may be a unit in itself, as for example, the sheet material might be retained in ring binders disposed transversely of the cover member, the particular style of binder and rack depending upon the material to be held. For illustrative purposes, I have shown

55 instances the binder and retainer may be a unit in itself, as for example, the sheet material might be retained in ring binders disposed transversely of the cover member, the particular style of binder and rack depending upon the material to be held. For illustrative purposes, I have shown

the binders of the character shown in Fig. 5 for containing the sheet material 15 and removably securing it in the retainer. In this instance the retainer is provided adjacent one of its side edges with a lip portion 18 providing a socket or recess adapted to receive one end portion of the strips 16, as shown in Fig. 2, while the opposite side of the retainer is provided with a lip 19 having an inwardly extending edge portion 20 for engaging the opposite end of the strips 16 and securing the same and their contents removably in the retainer. There is thus provided a structure whereby a group or a book of bound sheet material may be readily attached or detached from the cover for taking out to display the same. The type of retainer shown, as mentioned before, is for illustrative purposes. Rings or ring binders or any other type of device for securing the sheets, pages, booklets or the like can be employed for the purpose.

For securely holding the sheet material 15 in relatively fixed position with respect to the cover member 14 when the case is closed or in carrying position, a follower or flap 21 preferably of relatively broad dimension and extending substantially throughout the length of the cover member 14, is hingedly connected to one end portion of the cover member by means shown in the present instance as a strap 22 secured to one end portion of the cover, and formed preferably of webbing or the like, the strap 22 being shown in the present instance as laced through slits or openings 23 formed in the flap, the opposite or free end portion 24 of the strap 22 being adapted to engage a buckle 25 or other suitable connection, secured by a strip of webbing 26 or the like to the opposite end portion of the cover member 14.

It will be apparent that by such an arrangement, when the case is closed or in carrying position, the contents 15 may be secured snugly within the cover-member and case, and in relatively fixed position with respect thereto.

For supporting the lower edge portions of the material 15 when the case is in closed position, and to prevent sagging of the sheets and thereby place a strain on the binding thereof, the body member 11 is provided adjacent its bottom portion with a false bottom, spacer or filler 27, as clearly illustrated in Fig. 2, and which may be covered with a suitable fabric or soft covering material 28 to protect the edge portions of the sheets.

It will thus be seen that the device provides a display and carrying case consisting of two co-operating sections, as illustrated, elongated and more or less shallow sections, hinged together at meeting edges, one section provided with means disposed transversely of the section between one end and an intermediate position for detachably securing flexible sheet material to the section, the same extending transversely the section when inserted. The combined depth of the two sections is less than the width of the material to be held with the space in the section between the securing means and the opposite end providing a space for containing the free edges of the material when the same is in the position shown in Fig. 3 and the case is closed and locked. While the material is secured at one end when the case is closed for carrying, the weight of the same is more or less distributed throughout the length of the case. However, as was noted, the handle 33 may be disposed toward the bound edges of the sheets of material if required to secure perfect balance.

It will be noted that by reason of the base extension 12, the case has a substantial base portion to permit of supporting the case in substantially L-shaped position when open, as clearly illustrated in Fig. 1, thereby providing a structure which, even when open, will occupy a minimum of space on a table, desk or the like, and thereby avoid interference with other material, such for example, as samples or the like positioned on the table. It also presents an attractive appearance.

It will be apparent also that by positioning the binder rack 17 and binders mounted therein at one side of the central transverse plane of the cover and case, the contents, when the flap 21 is removed, are readily accessible and handy for reference use; also that by such an arrangement, the opposite end portion of the cover member is available for a tablet 29 or other material which may be found desirable to carry within the case.

As illustrated in Figs. 1, 2 and 3, the body portion of the case may be provided with a pocket 31, in which an order book 32, pictures, loose sheets or other similar article or articles may be carried.

Owing to the positioning of the binder bracket 17, the binders 16 mounted therein and the bulk of the sheet material contained in said binders adjacent one end portion of the cover member and case and at one side of the central transverse plane thereof, the carrying handles 33 are also preferably positioned at or adjacent the same side of the transverse central plane of the case in order to provide suitable balance for the contents thereof.

It will be apparent from the foregoing description that the present invention provides a strong rugged structure, capable of resisting bulging or sagging of the case due to the weight of the contents thereof, and wherein such contents are readily accessible, convenient for handling, and capable of being held securely in relatively fixed position with respect to the case when in carrying condition, or when being transported from one place to another.

Also that the present invention provides a construction and arrangement whereby a case of maximum capacity will occupy a minimum of space when in open or closed condition. The decreased thickness of the cover is compensated for by the increased length so that the capacity is not restricted, thus a maximum of material may be carried conveniently and comfortably, with the weight well distributed. The trim appearance, when closed, makes it attractive to the eye, and the convenience when open enables the salesman to find the desired material with a minimum of time and without groping around and fumbling for the same. It may be made of any suitable material, the dimensions being such as to fit the contents.

Obviously, the present invention is not limited to the precise construction and arrangement shown and described, as the same may be variously modified without departing from the spirit and scope of the invention as set forth in the appended claims.

What I claim as new and desire to secure by Letters Patent is:

1. In an article of the class described and in combination, a body member, a cover member hingedly connected thereto, a binder retainer mounted on the inner side wall of one of said members adjacent one end thereof and adapted to support a plurality of binders containing a

quantity of material therein, and a securing flap connected to said one of said members.

2. In an article of the class described and in combination, a body member, a cover member hingedly connected thereto, a binder retainer mounted on the inner side wall of said cover member adjacent one end thereof, a plurality of binders containing material mounted in said retainer, and means having portions secured adjacent the respective end portions of the cover member for securing the material in substantially fixed position with respect to said cover member.

3. In an article of the class described and in combination, a body member, a cover member hingedly connected thereto, a binder retainer mounted on the inner side wall of said cover member adjacent one end thereof, a plurality of looseleaf binders for containing sheet material removably mounted in said rack, a sheet engaging flap operatively related to said sheet material, and means having portions secured adjacent the respective end portions of the cover member and operatively related to said flap for clamping the flap snugly against contained material for securing the material in substantially fixed position with respect to said cover member.

4. In an article of the class described and in combination, a body member, a cover member hingedly connected thereto, a binder retainer mounted on the inner side wall of said cover member at one side of a plane extending transversely of the cover member adjacent the central portion thereof, a plurality of binders for containing material removably mounted in said retainer, a material engaging flap operatively related to said material, and connectable, manually operated means having portions secured adjacent the respective end portions of the cover member and operatively related to said flap for securing the flap snugly against said material to secure the same in substantially fixed position with respect to said cover member.

5. In an article of the class described and in combination, a body member, a cover member hingedly connected thereto, a binder retainer extending substantially one-half the length of said cover member and mounted on the inner side wall thereof at one side of a plane extending transversely of the cover member adjacent the central portion thereof, a plurality of binders for containing material removably mounted in said retainer, a material engaging flap operatively related to said material and hingedly connected to one end portion of said cover member, and means secured adjacent the opposite end portion of the cover member and operatively related to said flap for securing the flap snugly against said material and retaining the same in substantially fixed position with respect to said cover member.

6. A display and carrying case of the kind described, comprising two cooperating sections hinged together at meeting edges, one section provided with means disposed transversely of the section between one end and an intermediate point for securing flexible sheet material disposed on edge in the section, the combined depth of the two sections being less than the width of the material to be held, the space in the section between the securing means and the opposite end constituting a space for containing the folded over free edges of the material when the case is closed, and handle carrying means arranged on the exterior of the case at a point intermediate the ends, whereby the case and contents are in

balance when carried by said handle carrying means.

7. A display and carrying case of the kind described, comprising two cooperating sections hinged together at meeting edges, one section constituting a cover provided with finding means disposed transversely of the cover between one end and an intermediate point for binding and detachably securing flexible sheet material on edge in the cover and transversely thereto, the combined depth of the two sections being less than the width of the material to be held, the spaces in the sections between the said securing means and its opposite end providing a space for containing the free edges of the material when the material is fixed into overlapping relation therein and the case is closed.

8. A display and carrying case of the kind described, comprising two cooperating substantially elongated shallow sections hinged together at meeting edges, one section provided with means disposed therein transversely the section between the hinged edge and the free edge and at one side of a plane transversely of intersecting the section for detachably securing bound or unbound flexible sheet material to the section, the width of the sheet material between the bound edges and the free edges being greater than the combined depth of the two sections of the case, the space in the section at the opposite side of said transverse plane providing a compartment for containing the free edges of the material secured in the case, and means for retaining said free edges in said compartment when the case is closed.

9. In a case of the kind described and in combination, a receptacle body member, a cover member connected thereto, a retainer mounted transversely in the cover member, and a binder constructed to secure a quantity of sheets of material together, said binder detachably mounted in the retainer and disposed to hold the sheets on edge in the cover.

10. In a case of the kind described and in combination, a body member, a cover member comprising a face member provided with a flange on three of its edges and hingedly connected at its flangeless fourth edge to an edge of the body member, a binder retainer mounted on the inner side of the cover face member between the hinged edge and the opposite flanged edge, and constructed to engage the sheets adjacent one edge of each sheet with the sheets standing on edge and extending outwardly from the inner face of the cover member.

11. In a case of the class described and in combination, a body member constituting a tray consisting of a face member flanged about its edges, a cover consisting of a face member provided with a flange about three edges thereof and hingedly connected to one of the flanges of the tray, and sheet binder retainers mounted on the inner side of the cover face member adjacent one end of the cover, and a plurality of binders each arranged to hold a plurality of sheets detachably mounted in said retainers.

12. An article of the class described and in combination, a body member constituting a tray, a cover therefor hingedly connected thereto, a plurality of binder retainers mounted in said cover adjacent one end and extending across the same between the hinged edge and the opposite side of the cover, and a plurality of sheet binders removably secured in said retainers.

13. In a case of the kind described and in com-

bination, a body member consisting of a substantially rigid face wall provided with a flange about the periphery thereof, a cover therefor consisting of a substantially rigid face wall provided with a flange at three edges of the periphery thereof, and hingedly connected at the fourth edge to a flange of the body member, a plurality of retainers for sheet binders mounted on the face wall of said cover between one end and the transverse axis at the center, a plurality of binders for leaf material, one for each retainer detachably seated therein, and carrying means arranged on the case at substantially the center of gravity of the case when normally filled, whereby the case and contents are balanced when carried by the handle.

14. In a case of the class described and in combination, a flanged body member substantially

constituting a tray, a cover member consisting of a face side or bottom and flanged about three edges thereof and hinged at the fourth edge to the body member, a plurality of retainers mounted on the inner face of the cover between one end and the transverse axis thereof, a plurality of binders removably mounted in said retainers, each constructed to contain a quantity of sheet material therein, said sheet material normally standing on edge and extending outwardly from the cover member when the case is opened but flexible over toward the opposite end of the cover when the case is closed, and a shelf arranged within the body member at the hinged edge thereof for supporting the ends of said sheet material during the carrying of the case when closed.

LEO STEIN.
